US00D624875S

(12) **United States Design Patent**
Cowles

(10) **Patent No.:** **US D624,875 S**
(45) **Date of Patent:** **** Oct. 5, 2010**

(54) **TIRE VALVE STEM AND CAP WITH HAT**

6,612,329 B2 * 9/2003 Wright 137/232

(76) Inventor: **Andrew D. Cowles**, 13004 N. 161 E.
Ave., Collinsville, OK (US) 74021

* cited by examiner

(**) Term: **14 Years**

Primary Examiner—Stacia Cadmus

(21) Appl. No.: **29/353,702**

(74) *Attorney, Agent, or Firm*—Fellers, Snider, Blankenship,
Bailey & Tippens, P.C.; Dennis D. Brown

(22) Filed: **Jan. 13, 2010**

(57) **CLAIM**

(51) **LOC (9) Cl.** **12-15**

The ornamental design for a tire valve stem and cap with hat,
as shown and described.

(52) **U.S. Cl.** **D12/607**

DESCRIPTION

(58) **Field of Classification Search** D12/606-607;
D8/310; D9/300, 450, 445-446, 453; 152/427-429,
152/DIG. 7; 280/159, 847; D23/260; 74/558.5;
137/232; 139/89.1-89.4

See application file for complete search history.

The broken lines illustrating other structures or writing (e.g.,
“ACME PRODUCTS”) are included for the purpose of exem-
plifying environment and form no part of the claimed design.

The tire valve stem and cap with hat is shown on an enlarged
scale in FIGS. 2-4.
